(57) **CLAIM**

The ornamental design for a drain plug, as shown and described.

DESCRIPTION

FIG. 1 is a front perspective of a drain plug in a depressed state of use;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a front perspective view of a drain plug in an open state of use; and,

FIG. 10 is a view of a drain plug in an exploded state.

The broken lines in the drawings illustrate portions of the drain plug which form no part of the claimed design.
